Patented Dec. 1, 1914.

UNITED STATES PATENT OFFICE.

ALVIN O. CARMAN, OF TEKONSHA, MICHIGAN.

PUMP FOR VACUUM-CLEANERS.

1,119,748.

Specification of Letters Patent.

Patented Dec. 1, 1914.

Original application filed July 2, 1913, Serial No. 777,181. Divided and this application filed January 10, 1914. Serial No. 811,418.

To all whom it may concern:

Be it known that I, ALVIN O. CARMAN, of Tekonsha, in the county of Calhoun and State of Michigan, have invented certain new and useful Improvements in Pumps for Vacuum-Cleaners; and I do hereby declare the following to be a full, clear, and exact description of the invention, such as will enable others skilled in the art to which it appertains to make and use the same.

This invention relates to improvements in pumps and more particularly to such as are adaptable for use with vacuum cleaners, this application being a division of application filed by me on the 2nd day of July 1913, and designated by Serial No. 777,181.

The object of my present invention is to improve and simplify the pump construction of vacuum cleaners and to enhance the efficiency and ease of operation of the same.

With this and other objects in view, the invention consists in certain novel features of construction and combinations of parts as hereinafter set forth and pointed out in the claims.

In the accompanying drawings; Figure 1 is a view of a hand-operated vacuum cleaner embodying my improvements, a portion of the dust receptacle being broken away; Figs. 2 and 3 are enlarged sectional views illustrating the suction devices, and Fig. 4 is a horizontal sectional view taken above the piston.

1 represents a cylinder provided at its ends with packing boxes 2-3 for the accommodation of the two pipes 4-5, said pipes being connected with a piston 6 located within the cylinder.

The piston 6 is made hollow and divided by a partition 7 into two chambers 8-9 with which the pipes 4-5 respectively communicate. The upper and lower walls of the chamber 8 are provided with ports 10 communicating with the interior of the cylinder and the upper and lower walls of the chamber 9 are likewise made with ports 11 which also communicate with the interior of the cylinder.

Located within the chamber 8 are two hanger valves 12-12 for the ports 10, and these valves are connected by a link 13 pivotally attached at its ends to the respective valves,—said link being of such length that when one of said valves is closed, the other

will be open. Valves 14-14 for the ports 55 11 are hinged to the top and bottom faces of the piston and are connected by a link 15 pivotally attached at its ends to said valves 14 and passing through the piston chamber 9 and the ports 11, said link being 60 of such length to permit one of said valves to close when the other is open. The links 13 and 15 also serve to force one valve to close when the other opens and vice versa and thus prevent possibility of faulty operation on account of sticking of the valves.

The piston 6 is provided with a suitable peripheral packing 16 and in order to prevent the cylinder from rotary movement on the piston, a rod or bead 17 is provided 70 within the cylinder to move in a groove 18 disposed transversely across the peripheral wall of the piston.

The upper end of the tubular rod or pipe 3 may be bent to form a handle 18^a and a 75 handle 19 is secured, by means of arms 20, to the upper end of the cylinder, whereby the latter may be reciprocated on the two tubular rods or tubes 4-5 and cause a continuous flow of air upwardly through the 80 same, by reason of the coöperation of said cylinder with the valved piston with which the tubes communicate.

A flanged disk 21 is rigidly secured to the lower end of the lower tubular rod or 85 tube 4, and receives the upper end of a conical disk receptacle 22, the latter being removably attached to said disk by means of spring jaws 23. The lower end of the dust receptacle is provided with a short pipe section 24, which projects upwardly within said receptacle and to the depending end of this pipe section, the tubular shank 25 of an elongated nozzle 26, is secured by clamping means such as indicated at 27. At respective ends of the nozzle 26, two-wheeled trucks 28 are located; each of said trucks comprising a bar 29 pivotally attached between its ends to an end of the nozzle and having rollers 30 mounted at its respective 100 ends to run on the surface to be cleaned,—the rollers being thus arranged in front and in rear of the nozzle and affording means to maintain the mouth in proper relation to the surface to be cleaned and at the same 105 time permit the device as a whole to be rocked more or less during the operation of the same.

Within the dust receptacle, a dust screen 31 is removably disposed and may consist of a conical cage of woven wire covered with fabric, the lower portion of which latter projects upwardly through the bottom of the cage and receives the upper end of the pipe section 24.

By moving the nozzle over the surface to be cleaned and at the same time reciprocating the cylinder 1 on the valved piston 6, a continuous upward flow of air through the tubes will be caused and the suction thus created at the mouth of the nozzle will cause dust, etc., to enter said nozzle and find its 15 way to the dust chamber.

My improvements are simple in construction and may be operated effectually with minimum exertion.

Slight changes might be made in the details of construction of my invention without departing from the spirit thereof or limiting its scope and hence I do not wish to restrict myself to the precise details herein set forth.

Having fully described my invention

what I claim as new and desire to secure by Letters-Patent, is:—

A portable pump for vacuum cleaners, comprising a cylinder, a hollow piston therein divided into two chambers, two pipes disposed in parallel planes and passing freely through the heads of the cylinder at opposite sides of the centers of the respective heads, said pipes secured to the hollow piston and communicating with the respective chambers thereof, two oppositely disposed valves for each of said chambers, links disposed in said chambers and connecting the valves of each pair and positively insuring the opening of one valve 40 of each pair when the other valve of the same pair closes.

In testimony whereof, I have signed this specification in the presence of two subscribing witnesses.

ALVIN O. CARMAN.

Witnesses:

CHAS. H. ROGGE,
M. A. ESTES.
